CLAIM

The ornamental design for a combined knife and dressing tool for use primarily by a hunter, as shown and described.

DESCRIPTION

FIG. 1 is a top plan view of a combined knife and dressing tool for use primarily by a hunter showing my new design;

FIG. 2 is a side elevational view, the opposite side being a mirror image thereof;

FIG. 3 is a bottom plan view;

FIG. 4 is a rear elevational view; and

FIG. 5 is a front elevational view thereof.
